UNITED STATES PATENT OFFICE.

CARL JACOB JOHAN HÄGG, OF STOCKHOLM, SWEDEN.

MILKING-MACHINE.

1,266,795.

Specification of Letters Patent. Patented May 21, 1918.

Application filed March 25, 1918. Serial No. 224,588.

To all whom it may concern:

Be it known that I, CARL JACOB JOHAN HÄGG, a subject of the King of Sweden, residing at Stockholm, Sweden, have invented 5 new and useful Improvements in Milking-Machines, of which the following is a specification.

The present invention refers to a milking machine, in which the pressure plates for 10 working the teats are moved by means of a flexible pipe and a string in the same, belonging to a transmission device. In previously known milking machines of this kind the string only is connected with a driving 15 device, whereas the pipe is stationary at its one end. If the pipe has also to move a corresponding pressure plate, it is necessary that the string and the pipe have a sufficient bend. If they have not such a bend, 20 only that pressure plate connected with the string will move, whereas the pressure plate of the pipe will remain stationary and the pipe will only form a rest for the same. In consequence of the said bend, the pipe, 25 when the string is pulled, will move longitudinally, because the string tends to stretch and to move the pressure plate. Of course, this stretching will cause a considerable friction between the string and the 30 pipe. This friction requires an increase of power of the driving device, which increase unfavorably influences the economy of working of the machine. In consequence of the necessity of a sufficient bend of the string 35 and of the pipe, great lengths of these latter are needed and, consequently, greater costs arise. The string can move the pressure plate in one direction only, and thus special devices are needed for the return movement, 40 such devices causing complicated constructions and increased cost.

All these inconveniences are removed by the present invention by the fact that the string and the pipe work independently of 45 each other, each being connected with a special driving device, so that they will reciprocate in opposite directions. Thus a shorter stroke is needed than in the above named, previously known construction in which the 50 string only is operated by the driving mechanism and causes the entire movement, the movement being in the present case equally divided between the string and the pipe, thus effecting a saving of power. Two pipes, 55 which, together with their strings, are each connected at one end with a couple of pres-

sure plates, are connected at the other end, preferably yieldingly, each with one arm of a balance, the said balance being pivoted on a projection from one of two link points of 60 a link square, the said link points having a rectilinear movement, whereas the proper strings are connected with a similar balance of a projection from the other link point.

In the annexed drawings a form of construction of a milking machine according to the invention is illustrated. Figure 1 is a side elevation and partly a section of the machine. Fig. 2 is a plan view partly in section of the same. Fig. 3 is a section on line III—III in Fig. 2.

The working of the teats is effected by means of two pressure plates 2 for each teat placed in a teat covering. 3 is a flexible pipe or tube and 4 a string introduced into 75 the same. Both the pipe and the string have a reciprocating movement of the same stroke but in opposite directions. The movement of the pipe and of the string is facilitated by a link square 5. In each teat-covering, the top of one plate 2 is connected with a string 4, and the top of the other plate 2 with a pipe 3, the said plates receiving their movement from a link square 5, whereas the bottoms of these plates are in 80 the same way connected with an independent link square 5. The tops of all the plates are thus connected with one link square 5 and, in the same manner, the bottoms of all the plates are connected with another 90 link square 5. The two link squares 5 are (Fig. 3) placed one below the other. At their ends they are provided with two link points 6, moving in a straight line, which run, preferably by means of rollers 7, on 95 a guide rod 9 mounted in a casing 8 of the link squares 5. From each side of the link points there extends a projection 10. Each such projection has at its end a tap 12 which can slide in a sleeve and is surrounded by a coil spring 11. On this tap is pivoted a balance 13. The pipes 3 are pivotally connected with the front balances 13, and the strings 4 with the rear balances. Each link connecting piece 14 of the upper and lower link square 5 is connected with a flexible pipe 15 and with a string 16 introduced into this latter. Between the two link connecting pieces 14 of both link squares 5, a coil spring 17 is placed around 110 the string 16. The pipe 15 and the string 16 receive a sliding movement in opposite

directions from a suitable driving device not shown (for instance from a special driving device constructed by the inventor for the present milking machine), so that the 5 link connecting pieces 14 will move to and from each other, thereby causing the link points 6 to move to and from each other. Thus the pipes 3 and the strings 4 will as seen, by the same stroke receive a sliding 10 movement in directions opposite to each other and give the milking movement to the plates 2. During this operation the balances 13 adjust their movement to various 15 teat thicknesses, and the coil springs 11 cause the plates 2 to rest yieldingly upon the teats. By employing the link squares in the manner described, several advantages 20 are gained. Thus, for instance, the pressure plates receive a suitable closing movement, the speed of the movement of the link 25 square from an inner to an outer position of the link points 6 decreasing.

The details of the present invention can vary as regards material, number, form, 25 size and composition, and can be reversed, as long as the characteristic features of the invention are retained.

What I claim is:

1. A milking machine comprising 30 movable pressure plates for working the teats, means for actuating said plates comprising flexible members, flexible pipes incasing said members, said pipes and members being connected at one of their ends to said plates 35 and capable of reciprocating movement in opposite directions, balances connecting the opposite ends of said pipes and members, a link square having two link points capable of rectilinear movement, said balances being 40 yieldingly mounted on said link square, and means for actuating said link square to impart reciprocating movements in opposite directions to said balances.

2. A milking machine comprising 45 movable pressure plates, flexible means for actuating said pressure plates, reciprocating

flexible means controlling the last means and movable at right angles thereto, and means operatively connecting the last means to the first means for reciprocating the 50 latter.

3. A milking machine comprising movable pressure plates, flexible members connected to said pressure plates, pipes connected to said pressure plates, and a link 55 square for reciprocating said pipes and members in opposite directions.

4. A milking machine comprising movable pressure plates, flexible members connected to said pressure plates, a pair of projections mounted for reciprocating rectilinear movements in opposite directions, said members being connected to said projections, and means for actuating said projections whereby said members will be 60 reciprocated in opposite directions.

5. A milking machine comprising movable pressure plates, a link square biased to a predetermined position, flexible members connecting said link square with said plates, 70 means interposed between said link square and said flexible members to permit automatic adjustment of said members with relation to said link square, and means for actuating said link square against its bias. 75

6. A milking machine comprising movable pressure plates, a pair of projections mounted for reciprocating rectilinear movement, a link square for actuating said projections in opposite directions, flexible 80 members connecting said projections with said plates, and means for actuating said link square whereby said flexible members will be reciprocated in opposite directions.

In testimony whereof I have signed my 85 name to this specification in the presence of two subscribing witnesses.

CARL JACOB JOHAN HÄGG.
